UNITED STATES PATENT OFFICE.

WILLIAM TURNBULL, OF PECORIA, ILLINOIS, ASSIGNOR TO THE HOLT MANUFACTURING COMPANY, OF STOCKTON, CALIFORNIA, A CORPORATION OF CALIFORNIA.

TRACTION-ENGINE.

1,304,416.

Specification of Letters Patent. Patented May 20, 1919.

Application filed May 25, 1918. Serial No. 236,521.

To all whom it may concern:

Be it known that I, WILLIAM TURNBULL, a citizen of the United States, residing at Peoria, in the county of Peoria and State of Illinois, have invented new and useful Improvements in Traction-Engines, of which the following is a specification.

This invention relates to tractors of the type shown and described in my application, Ser. No. 77,382, filed February 10th, 1916, and has for its object to simplify and improve the manufacture and assembly of the machine, and particularly to render the transmission mechanism readily accessible.

In this earlier application I have shown and described a one-piece cast metal frame which is adapted to support the entire transmission mechanism. Although the transmission case cover in that case is removable, it is very difficult to get out the transmission to effect any adjustments or repairs and often requires dismantling of a considerable part of the traction engine to get down into the bed where the various gears and shafts are located.

In the present instance I so build the frame and transmission case cover and rearrange the transmission that the transmission mechanism is supported upon and carried by the transmission case cover and is removable as a unit therewith. The advantages of such a construction are obvious. In carrying out the invention the lower portion of the transmission housing forms part of the main frame, being either cast integrally therewith or otherwise built into it as an indispensable part thereof. Such a construction affords great convenience in manufacture and assembling and provides a rigid structure, eliminating to a great extent the use of bolts and riveting means with the resulting possibility of loose joints.

These one-piece cast or structural metal frames are designed for heavy duty work in traction engine construction employing endless, self-laying tracks of the chain track principle. It has not been thought necessary to illustrate these chain tracks because their operation is well understood, and the method of use of these metal frames in traction engine construction is illustrated in my earlier application above mentioned.

One form which my invention may assume is exemplified in the following de-

scription and illustrated in the accompanying drawings, in which—

Figure 1 shows a plan view of a one-piece main frame construction formed integrally with which is the lower portion of the transmission housing.

Fig. 2 shows a side elevation of the same.

Fig. 3 shows a front end elevation.

Fig. 4 shows a vertical, central, longitudinal, sectional view of the transmission mechanism arranged within the housing and supported entirely upon the detachable cover of said housing.

Fig. 5 shows a plan view of the rear end of the frame, parts of the driving mechanism being shown in cross-section.

Fig. 6 is an exterior side elevation of Fig. 4.

As shown in the drawings, the main frame comprises parallel side bars 10, a front end piece 11, forward cross sills 12 and rearward cross sills 13, and the lower half 14 of the transmission housing, all cast in one piece.

An axle 15 carrying at each end a sprocket driving wheel 16 is journaled upon the lower portion of the transmission housing at the exterior thereof in bearings 15^a, and forwardly of the axle is a divided drive shaft 18 extending through either side of the lower portion of the housing, there being on the outer end of each portion of shaft 18, exterior of the housing, a pinion 19 meshing with a spur gear 20 fixed upon the hub of the adjacent sprocket driving wheel. The inner end of each portion of shaft 18 carries a spur gear 22 receiving power from change speed transmission mechanism presently to be described, and which transmission mechanism is carried entirely upon the cover or detachable upper portion 14^a of the transmission housing.

This transmission mechanism includes an engine shaft 23 extending longitudinally of the main frame and journaled in roller bearings carried by tubular member 24 formed on the forward end of the cover, said engine shaft having at its rear end a constantly rotating gear 25. In line with the engine shaft is the main shaft 26 of a change speed gear set, journaled at its forward end in ball bearings 27 carried within the gear 25 and at its rear end journaled in roller bearings carried by a divided ring

28, the upper portion of which ring is formed integrally with the cover and the lower half of which is formed on an arm 29 bolted to said cover. The shaft 26 has 5 a high speed driven gear 30 and a low speed driven gear 31 splined thereon and slidable in unison by shift mechanism of any suitable form, not shown. The gear 25 is constantly in mesh with a gear 32 on a countershaft 10 33, which countershaft, as shown in Fig. 4, is arranged below the main shaft and journaled at opposite ends in roller bearings, the bearings at the forward end being carried in a ring 34 formed integrally with 15 the tubular extension 24 and at the rear end in a ring 35 formed upon the arm 29.

Fixed upon the countershaft is a high speed driving gear 36 adapted to be engaged by the gear 30 and a low speed driving 20 gear 37 adapted to be engaged by the gear 31, also a reverse gear 38 meshing with an idler gear 39 on a separate support 40 carried by the cover. The idler gear 39 is in turn engaged by the gear 31. 25 The above described change speed gear set is in principle substantially like that shown and described in my prior application before referred to, and is to be considered merely as one form of a variety of 30 arrangements which may be employed in carrying out my invention.

The rear end of the main shaft 26 carries a bevel pinion 41 which meshes with a bevel gear 42 on a transverse drive shaft 43. This 35 transverse shaft carries right and left sprocket driving sleeves 44, each arranged to be connected to the shaft 43 by means of an individual friction clutch mechanism 45 of the multiple disk type, controllable in 40 the manner shown and described in my prior application above referred to, whereby to steer the vehicle. The shaft 43 and sleeves 44 are journaled in a divided bearing 46, the upper portion of which is integral 45 with the cover and the lower portion of which is formed integral with the arm 29. Each sleeve 44 has a pinion 47 to mesh with the adjacent spur gear 22 before referred to.

The operation of the above described 50 transmission mechanism is the same as that shown and described in my prior application before referred to.

At the top portion of the cover 14^a in a plane with the main shaft 26 is a power 55 shaft 48 for supplying power for exterior purposes, as, for instance, driving a belt pulley. This power shaft is above the countershaft as well as the main shaft and receives its turning movement through a pinion 56 meshing with the constantly rotating pinion 25. The forward end of the power 60 shaft is journaled in roller bearings supported by a ring 57 formed on the forward end of the cover of the transmission housing, and the rear end of the power shaft 65

is supported upon bearings carried in a ring 52 fixed to the end of the cover.

It will be noted that, except for the axle 15 of the sprocket wheels and the divided drive shaft 18, all parts of the transmission 70 mechanism, including the change speed gear set and the power shaft for the belt pulley, are carried entirely by the cover of the transmission casing. This cover is fitted detachably upon the lower portion of the 75 casing and is bolted tightly thereon so that the casing is entirely inclosed in the usual manner. When it is desired to remove the transmission mechanism the cover is taken off bringing with it the gear set and associated parts without disturbing the lower portion of the casing, which forms an indispensable part of the main frame.

Aside from the advantage of accessibility 80 of the parts of the transmission mechanism, 85 this manner of mounting the gears on the cover provides a still greater advantage in that the lower half of the transmission housing does not have to be machined to the extent that would be necessary if the bearings for the various shafts of the transmission mechanism were formed thereon, since the lower portion of the housing forms a part of the main frame and is therefore quite heavy and cumbersome and it will be 90 realized that the task of machining bearings thereon is difficult. Also with the transmission parts so arranged upon a small unitary frame, such as the cover 14^a, it becomes 95 much easier to assemble the machine.

Having thus described my invention, what I claim and desire to secure by Letters Patent is—

1. In a self-propelled vehicle, a main 100 frame, a transmission mechanism carried thereby, a housing for the transmission mechanism, the lower portion of which forms an integral part of the main frame, a detachable cover for said housing, and a change speed gear set forming part of the 105 transmission mechanism within said housing carried by the cover and removable there-with.

2. In a self-propelled vehicle, a main 110 frame, a transmission mechanism carried 115 thereby, a housing for the transmission mechanism, the lower portion of which forms an integral part of the main frame, a detachable cover for said housing, a change speed gear set forming part of the transmission mechanism carried within said housing and supported upon the cover, a power shaft carried also upon said cover within the casing, and means for operatively connecting said power shaft with the transmission 120 mechanism.

3. In a self-propelled vehicle, a main 125 frame forming a part of a base portion of a gear housing, sprocket driving wheels journaled in the lower portion of the housing, a 130

detachable cover for the housing, and a transmission mechanism carried by the cover, including a change speed gear set for driving said sprockets.

- 5 4. In a self-propelled vehicle, a main frame forming a part of a base portion of a gear housing, a pair of sprocket driving wheels journaled independently of each other, one on each side of the gear housing, a main
10 detachable cover for the housing, a transmission mechanism, including a set of change speed gears carried within the housing upon said cover, and removable therewith, and individual friction clutch members exterior of and carried by the cover for driving each sprocket.

15 5. In a self-propelled vehicle, a main frame forming a part of the lower portion of a gear housing, final driving gears for rear wheels on the vehicle journaled in the lower portion of said housing, a detachable cover for the casing, and a transmission mechanism carried on said cover for transmitting power from said transmission to
20 drive the driving gears.

25 6. In a self-propelled vehicle, the combination of a one-piece cast metal frame having formed integrally therewith the lower part of a transmission housing, and a detachable cover for said transmission housing with a variable speed gear transmission mechanism carried on the cover, and removable therewith as a unit.

30 7. In a self-propelled vehicle, a transmission mechanism carried thereby, a housing for the transmission mechanism, a cover for said housing, a variable speed gear transmission mechanism carried by the cover, and removable with the same, a pair of driving members journaled in the housing, and means for transmitting power from the variable speed gear transmission to either of
35 said driving members or to both in unison.

40 8. In a self-propelled vehicle, a main frame, a transmission mechanism carried thereby, a housing for the transmission mechanism, a detachable cover for said housing, a variable speed gear transmission carried by the cover and removable with the same, a drive shaft also carried by the cover and removable therewith, means for transmitting power from the variable speed gear transmission to the drive shaft, a pair of driving members journaled in the housing, and means for transmitting power from the drive shaft to either driving member or both in unison.

45 9. In a self-propelled vehicle, a main frame, a transmission mechanism carried thereby, a housing for the transmission mechanism, a detachable cover for said housing, a variable speed gear transmission carried by the cover and removable with the same, a drive shaft also carried by the cover and removable therewith, means for transmitting power from the variable speed gear transmission to the drive shaft, a pair of driving members journaled in the housing, and means for transmitting power from the drive shaft to either driving member or both in unison.

50 10. In a self-propelled vehicle, a main frame, a transmission mechanism carried thereby, a housing for the transmission mechanism, the lower portion of which forms an integral part of the main frame, a detachable cover for said housing, a variable speed gear transmission journaled in and carried by the cover, a pair of driving members journaled in the transmission housing, and means for transmitting power from the variable speed gear transmission to drive either driving member or both in unison either reverse or ahead.

55 11. In a self-propelled vehicle, a main frame, a transmission mechanism carried thereby, a housing for the transmission mechanism, the lower portion of which forms an integral part of the main frame, a detachable cover for said housing, a variable speed gear transmission journaled in and carried by the cover, a drive shaft carried by the cover and removable with the same, a pair of driving members journaled one on each side of the housing, means for transmitting power from the variable speed gear transmission to drive the drive shaft either reverse or ahead, and means for transmitting power from the drive shaft to drive either driving member or both in unison.

60 12. In a self-propelled vehicle, a main frame, a transmission mechanism carried thereby, a housing for the transmission mechanism, the lower portion of which forms an integral part of the main frame, a detachable cover for said housing, a variable speed gear transmission journaled in and carried by the cover, a drive shaft carried by the cover and removable with the same, a pair of driving members journaled one on each side of the housing, means for transmitting power from the variable speed gear transmission to drive the drive shaft either reverse or ahead, a divided shaft journaled in the transmission housing, means for transmitting power from the drive shaft to drive either section of the divided shaft or both sections in unison, and means for transmitting power from each section of the divided shaft to drive each driving member.

65 13. In a self-propelled vehicle, a main frame, a transmission mechanism carried thereby, a housing for the transmission mechanism, the lower portion of which forms an integral part of the main frame, a detachable cover for said housing, a variable speed gear transmission journaled in and carried by the cover, a drive shaft car-

ried by the cover and removable with the same, a pair of driving members journaled one on each side of the housing, means for transmitting power from the variable speed 5 gear transmission to drive the drive shaft either reverse or ahead, a divided shaft journaled in the transmission housing, a pair of friction clutches carried by the drive shaft, means for transmitting power through each 10 friction clutch to drive each section of the divided shaft, and means for transmitting power from each section of the divided shaft to drive the driving members.

14. In a self-propelled vehicle, a main 15 frame, a transmission mechanism carried thereby, a housing for the transmission mechanism, the lower portion of which forms an integral part of the main frame, a detachable cover for said housing, a variable speed gear transmission mechanism carried by and removable with the cover, a pair of driving members journaled in the transmission housing, a drive shaft carried by the cover and removable therewith, said 20 drive shaft extending through each side of the cover, means for transmitting power from the variable speed gear transmission to drive the drive shaft, a friction clutch on each end of the drive shaft exterior of the cover, a divided shaft journaled in the transmission housing, means for transmitting power through the friction clutches to drive each section of the divided shaft either independently or in unison, a pair of driving sprockets journaled one on each side of the transmission housing, and means for transmitting power from each section of the divided shaft to drive each adjacent driving 25 sprocket.

15. In a self-propelled vehicle, a main

frame, a transmission mechanism carried thereby, a housing for the transmission mechanism, the lower portion of which forms an integral part of the main frame, 35 a detachable cover for said housing, a variable speed gear transmission mechanism carried by and removable with the cover, a pair of driving members journaled in the transmission housing, a drive shaft carried by the cover and removable therewith, said drive shaft extending through each side of the cover, means for transmitting power 40 from the variable speed gear transmission to drive the drive shaft, a friction clutch on each end of the drive shaft exterior of the cover, a divided shaft journaled in the transmission housing, means for transmitting power through the friction clutches to drive each section of the divided shaft either independently or in unison, a pair of driving sprockets journaled one on each side of the transmission housing, and means for transmitting power from each section of the divided shaft to drive each adjacent driving 45 sprocket.

In testimony whereof I have hereunto set my hand in the presence of two subscribing 50 witnesses.

WILLIAM TURNBULL.
